UNITED STATES PATENT OFFICE.

GEORGE MEHR, OF PHILADELPHIA, PENNSYLVANIA.

IMPROVEMENT IN SUN-DIALS.

Specification forming part of Letters Patent No. **155,327**, dated September 22, 1874; application filed May 22, 1874.

To all whom it may concern:

Be it known that I, GEORGE MEHR, of the city and county of Philadelphia, and State of Pennsylvania, have invented a new and Improved Sun-Dial; and I do hereby declare that the following is a full, clear, and exact description of the same, reference being had to the accompanying drawing, forming a part of this specification, in which—

Figure 1 is a perspective view; Fig. 2, a side, and Fig. 3 a front, elevation.

The invention relates to a novel construction and notation of dial, by which the correct time of day may be exhibited by the sun in a position inclined toward, and convenient to, the passer-by on the streets and thoroughfares of cities and towns, enabling all, without difficulty or delay, to perceive the solar time.

A represents a cross fitted in a suitable socket, block, or bracket, and inclined at such an angle to a horizontal plane as corresponds with the degree of latitude in which the locality of the dial may be situated. B C D E are the four arms of cross, of which the three former are provided with hemispherical concavities B' C' D', quadrantly divided by partitions b c d.

As the sun rises, the division b will throw a shadow on the left side of concavity B', and the arm B on the right side of the arm C. This will gradually withdraw, on the scales c¹ b¹, in the direction of the division b and the intersection of arms C B until six o'clock,

when it will disappear. Reappearing on the right of division b and the left of division c, it will advance up the scales b² c² e³, and, after nine o'clock, up the scale d², until the sun attains its meridian, when all shadows will again disappear. As the sun declines, the shadow of division c d and of arms D C will pass over the scales or dials c³ d³ e³ b³. At six o'clock the shadow will again momentarily disappear, and then, resuming its course, pass over the dial-scales c⁴ d⁴.

It will be observed that the dial-scales c¹ d² e² b³ e³ c⁴ are fractional, and together make up the day's notation, while the two opposite concave scales make a perfect dial, and the middle-arm scale (side and concave) another.

Having thus described my invention, what I claim as new, and desire to secure by Letters Patent, is—

1. A sun-dial made in the shape of a cross, B C D E, having partitioned end concavities B' C' D', in three of the arms, and a system of time-scales, b¹ c¹ b² c² d² e² b³ c³ d³ e³ c⁴ d⁴, arranged as shown and described.

2. A dial having three concavities on the ends of cross-arms, with diametrical partitions, arranged and notated as and for the purpose specified.

GEO. MEHR.
